(57) **CLAIM**

The ornamental design for a sperm sampler, as shown and described.

DESCRIPTION

FIG. 1 is a front elevation view of the sperm sampler according to the invention;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a cross-sectional view of the sperm sampler through line 7-7 shown in FIG. 1;

FIG. 8 is a cross-sectional view of the sperm sampler through line 8-8 shown in FIG. 4;

FIG. 9 is a cross-sectional view of the sperm sampler through line 9-9 shown in FIG. 2;

FIG. 10 is a perspective view thereof; and,

FIG. 11 is another perspective view thereof.
